UNITED STATES PATENT OFFICE.

JOHN HENRY SILLEY, OF LONDON, ENGLAND.

DOOR FOR FURNACES, &c.

SPECIFICATION forming part of Letters Patent No. 762,850, dated June 14, 1904.

Application filed October 23, 1903. Serial No. 178,259. (No model.)

To all whom it may concern:

Be it known that I, JOHN HENRY SILLEY, of London, England, have invented a new and useful Improvement in Smoke-Box, Furnace, and other Doors for Boilers and the Like, of which the following is a specification.

This invention relates to smoke-box, furnace, and other doors for boilers and the like, and has for its object the provision of means for quickly and readily fastening the said doors in their closed position so that they are supported around their edges in such a way that they make a tight joint upon the smoke-box, furnace front or casing to which they are attached and on which they bear.

Considerable difficulty has been experienced in the past in maintaining smoke-box and furnace doors tight and in working condition on boilers working under natural, induced, or forced draft, owing to the buckling of the doors and casings when subjected to air pressure and high temperature, and by this invention I entirely overcome the above disadvantages.

To carry this invention into effect, I arrange upon the casing a series of hooks or clutches around the parts adjacent to the edges of the door, and close to each series of catches I mount a device adapted to swivel in bearings and at the same time have a sliding movement in the direction of its axis. This device carries a series of wedge-fasteners of the same number as there are hooks or catches in that particular series. I construct the device of a girder formation, such as of angle-iron section or other section having transverse stiffness, so as to give a continuity of support to the edge of the door. One simple method of construction of the wedge-fasteners is by cutting a series of notches having inclined faces out of the web of the angle-iron, the inclined faces of which are adapted to engage with the hooks or catches. The fastening device and the hooks or catches may be both on the casing, or one may be on the door and the other on the casing, the only essential feature being that when they coact the door and casing are brought into intimate contact with one another. When the door is fastened and it is desired to open it, the device is slid up in its

bearings in an axial direction, so as to disengage the inclined faces with the hooks or catches, and is then turned about its axis, so as to clear the catches and allow the door to open.

In order that the invention may be the better understood, I will now proceed to describe the same in relation to the accompanying drawings, reference being had to the letters marked thereon.

Like letters refer to like parts in the various figures.

Figure 1 is a perspective view of the sliding fastening device which forms the essential part of my invention. Fig. 2 is a view of the smoke-box door mounted on a vertical axis and provided with my fastening device on all four sides. Fig. 3 is a similar view of the door mounted on the horizontal axis having my invention applied to three of its sides. Fig. 4 is a view of the furnace-door with my invention applied thereto. Fig. 5 is a part sectional view of the device applied to a smoke-box door in its fastened position. Fig. 6 is a front elevation of the same. Fig. 7 is a view of Fig. 5, showing the device drawn back from engagement with the hooks or catches, but not turned over. Fig. 8 is a view of the device turned over, showing the door ready for opening. Fig. 9 is an enlarged sectional view of the device and the catches on the line *u v* of Fig. 6. Fig. 10 is an enlarged sectional view of the same on the line *w x* of Fig. 7. Fig. 11 is an enlarged sectional view of the same on the line *y z* of Fig. 8. Figs. 12, 13, 14, and 15 are various views of the brackets on which the device slides.

Referring now to Fig. 1, it will be noticed that the fastening device *a* consists of an angle-iron having inclined surfaces *b* and spindles *c*. It is also provided with a handle *d*, by which its operation is effected, while a notch *e* is made in the web of the angle-iron to permit of the whole device being swung about the axis of the spindles *c* clear of the hooks or catches. The spindles *c* are inserted into brackets *f*, which are mounted either on the casing or on the door, as the case may be. For example, in Fig. 2 all the devices *a* with their brackets *f* are mounted on the door, in

Fig. 3 two of the said devices *a* and their brackets *f* are mounted on the door at the sides and at the bottom device *a* with its brackets *f* is mounted on the casing, and in Fig. 4, which 5 illustrates a furnace-door, the device *a* and its brackets *f* are mounted on the furnace front or casing. The device *a* is so mounted in its brackets *f* that it can slide longitudinally in the direction of the axis of the spindles *c*.
10 Adjacent to the edges of the door hooks or catches *g* are mounted on the casing, these catches having a projecting lip or ledge under which the inclined faces *b* on the device *a* engage.
15 Referring now to Figs. 5, 6, 7, and 8, it will be noticed that when the device *a* is slid down so that the inclined surfaces *b* engage with the hooks or catches *g* the door is forced into close contact with the surfaces of the casing on which 20 it rests, and the stiffness of the vertical web of the angle-iron-section girder serves to give support with great transverse rigidity to the door. When it is desired to open the door, the device *a* is slid back longitudinally, so that 25 the inclined portions *b* become disengaged from the hooks *g*, as shown in Fig. 10, and the device *a* can now be turned upon the axis of the spindles *c*, so as to be quite clear of the hooks *g*, as shown in Fig. 11, when the door 30 can be opened. It will be noticed in reference to Figs. 12, 13, 14, and 15 that the brackets *f* are provided with an extension *h*, which serves as a stop to prevent any sliding of the device *a* in the brackets *f* at any other position 35 than that in which the device *a* is to be slid axially in order to lock or unlock the door. This action is effected by the end of the angle-iron *i* when the turning of the device *a* takes

place abutting against the end of the portion *h* of the brackets *f*, the undercut portions of 40 the extension *h* allowing of the sliding of the device when it has been turned into its proper position for sliding engagement. The inclined faces *b* and the surfaces of the hooks or catches *g*, with which they engage, are given an in- 45 clination transverse to their length, as shown in Figs. 9, 10, and 11, so as to form a dovetail locking effect in order to prevent the device *a* from being forced out of engagement from the hooks or catches *g*.
50

What I claim as my invention, and desire to secure by Letters Patent, is—

1. In a casing, a door, a sliding device of great transverse rigidity carried by one of said parts adapted to give continuity of support 55 along the edge of the door, a series of catches mounted on the casing, said sliding devices having inclined surfaces arranged to engage with the said catches so as to force the door and casing into close contact, substantially as 60 described.

2. In a casing, a door, brackets mounted on one of said parts, a series of catches on the casing, and a device of great transverse rigidity adapted to slide and be rotated in the 65 brackets and having inclined surfaces along its length slidingly engaging with the said catches so as to force the door and casing into close contact, substantially as described.

In witness whereof I have hereunto set my 70 hand in presence of two witnesses.

JOHN HENRY SILLEY.
